UNITED STATES PATENT OFFICE.

MIECZYSŁAW BARABASZ, OF BALTIMORE, MARYLAND, ASSIGNOR OF TWO-SIXTHS TO AUGUST F. P. STENZY AND ONE-SIXTH TO STEPHANIA BARABASZ, OF BALTIMORE, MARYLAND.

TOOTHLESS BUCKLE.

No. 801,502.

Specification of Letters Patent.

Patented Oct. 10, 1905.

Application filed April 12, 1905. Serial No. 255,089.

To all whom it may concern:

Be it known that I, MIECZYSŁAW BARABASZ, a citizen of the United States, residing at Baltimore, in the State of Maryland, have invented certain new and useful Improvements 5 in Toothless Buckles, of which the following is a specification.

This invention relates to improvements in suspender-buckles, and has for its object to provide a buckle of improved construction which shall be formed from a single piece of metal and without teeth and having a plurality of cross-bars which reinforce the buckle in a crosswise direction and at the same time afford a curved surface around which the suspender-strap may pass with only sufficient friction to prevent slipping, and thus enable the buckle to be easily adjusted on the strap without injury to the latter.

Figure 1 illustrates a side or face view of the buckle attached to a suspender-strap. Fig. 2 illustrates a sectional view of the buckle with the strap or web fed therethrough to form a loop. Fig. 3 illustrates a flat side view 25 of the detached buckle. Fig. 4 illustrates an enlarged sectional view of the buckle to clearly show the construction of the cross-bars, and Fig. 5 shows an edge view of the same.

Referring to the drawings, it will be seen 30 that the buckle is stamped or formed from a single plate and comprises a metal plate which is curved in a lengthwise direction and having two side or end bars *b*, a straight cross-bar *c*, connecting the side bars at one end, and a curved cross-bar *d*, which also connects the side bars *b* at the opposite end. This latter cross-bar is arched or curved in a longitudinal direction, so as to fit close against the wearer and also for the purpose of forming 35 a curved recess *d'*, through which the web or strap may pass freely and without undue friction when adjusting the buckle. Adjacent the cross-bar *d*, which is the top bar, the plate is provided with a cross-bar *g*, and the lower 40 side of the cross-bar *d* is provided with an inwardly-projecting stationary tongue *f*, whose edge *f'* is straight as compared to the longitudinal arch or bend in said cross-bar *d*, as will clearly be seen in Fig. 5. Below the slot 45 *e* the buckle is provided with a cross-bar *g*, which connects the two side or end bars *b*, and in cross-section this bar *g* is curved outwardly, the metal being bent or forced outwardly at

g' from the inner concave side of the buckle-plate. This curved cross-bar forms a smooth 55 rounded surface around which the web *a* may pass without injury. Below the rounded cross-bar *g* the buckle is provided with a tubular cross-bar *h*, which has a flat outer surface *h'* and a convex inner surface *h''*, which is formed 60 by bending the metal from opposite edges of the bar *h* backwardly toward the concave side of the buckle and abutting said edges at the inner side of the buckle, as can be plainly seen in Fig. 4. By the formation of this tubular 65 bar *h* the buckle will have slots *i* and *j* at opposite sides of said tubular bar.

In attaching the buckle to the strap or web *a* the end *a'* of the strap is passed through the lowermost slot *j* from the inner concave side 70 of the buckle and then turned down on the outer convex side of the buckle and over the lower cross-bar *c*, and said end is then secured, preferably by stitches *k*, to the strap *a* below the buckle. A loop *l* is then formed by the 75 strap hanging pendently from the lower bar *c*, and the strap then extends upwardly from said loop and passes from the outer convex side of the buckle through the slot *j* and around the convex surface *h''* of the tubular bar *h*, 80 then through the slot *i* again to the outer side of the buckle and around the outwardly-curved side *g'* of the bar *g*, then through the slot *e* again to the inner concave side of the buckle and around the edge *f'* of the stationary tongue 85 *f*, and finally up through the recess in the bar *d*, formed by the curvature of said bar, and the upper end *a''* of the strap may then pass over the shoulder of the wearer.

It will be understood that any strain or pull 90 on the upper end *a''* of the strap while the loop *l* is held stationary will simply cause the edge *f'* of the stationary tongue to bite into the strap, while below the tongue the strap will pass around the convex bar *g* and the tubular 95 bar *h* and be held sufficiently by friction to prevent slipping.

Having thus fully described my invention, what I claim as new, and desire to secure by Letters Patent, is—

1. A buckle of a single piece of metal comprising a plate having parallel side bars and a cross-bar at each end of said side bars and the upper cross-bar having a stationary tongue which projects inwardly from its lower edge 105 and said buckle also having a cross-bar adja-

cent said tongue which has a convex outer surface and a tubular cross-bar adjacent the lower cross-bar which has a convex inner surface.

2. A buckle of a single piece of metal comprising a plate having parallel side bars and a cross-bar connecting the side bars at each end of the latter and the lower side of the upper cross-bar having a stationary tongue which projects toward the inner side of the buckle, 5 said buckle also having a cross-bar which is convex on its outer side and a tubular cross-

bar which is convex on its inner side and said tubular bar having position between the lowermost cross-bar and the bar with the convex outer side.

In testimony whereof I affix my signature in presence of two witnesses.

MIECZYSLAW BARABASZ.
